OVERALL GARMENT

Cecil C. Garrett and Eugene A. Lockwood, High Point, N. C., assignors to High Point Overall Company, High Point, N. C., a corporation of North Carolina

Application April 19, 1934, Serial No. 721,376

1 Claim. (Cl. 2—227)

This invention relates to a garment and more especially to that type of garment known as overalls.

It is an object of this invention to provide in 5 an overall construction, a re-enforced and new type of back having great strength, ease of wear, long life and other new and improved features.

Heretofore, it has been customary to form the suspender portion of overalls from the same piece 10 of fabric as the leg portion but by crossing the pieces of fabric so that the right leg is extended to form the left suspender and the left leg is crossed over to form the right suspender. These overlapping portions are stitched together thus 15 causing an overlapping of the fabric and results in a plurality of seams, and as overall material is very heavy, it forms welts and ridges which are uncomfortable to the back of the wearer.

It is a further object of this invention to provide 20 an overall in which the suspenders are formed of the same piece of material as the leg without crossing the suspenders, in other words, the right leg is extended to form the right suspender and the left leg is extended to form the left suspender and 25 a suitable re-enforcing and supporting patch is sewed onto the exterior of the two leg and suspender portions to not only re-enforce the seam joining the leg and suspender portions together, but also to form a support for that portion of the 30 back over which it is disposed.

Some of the objects of the invention having been 35 stated, other objects will appear as the description proceeds when taken in connection with the accompanying drawing, in which:—

Figure 1 is a rear elevation of the overalls;

Figure 2 is an enlarged rear elevation of the upper portion of Figure 1, omitting the figure of the man and showing the re-enforcing patch partially ripped therefrom to better disclose the 40 nature of the invention;

Figure 3 is an enlarged cross-sectional view taken along the line 3—3 in Figure 1.

Referring more specifically to the drawing, the numerals 10 and 11 indicate the two leg portions 45 of the garment which are joined together in the usual manner by seam 12. The piece of fabric out of which the leg portion 11 is made is extended upwardly and has suspender 11a integral therewith. The portion out of which the leg 10 of the 50 overall is made, is extended upwardly and has the

suspender 10a integral therewith. After the two legs and suspender portions are secured to each other by the usual seam 12, a re-enforcing portion 13, shown as being diamond-shaped, is stitched on the exterior of the portions 10a and 11a which not only re-enforces the seam 12 and 5 prevents tearing or ripping at the point A, but also forms a support for that portion of the back covered by the portion 13.

Secured to the portions 10a and 11a are the elastic members 14 and 15 which are inserted into the portions 10a and 11a as at 18 and 21 and suitable stitching is employed for stitching the portions 14 and 15 to the portions 10a and 11a as shown in Figure 2. Portion 14 has a hook 17 for 10 engaging a suitable button on the bib of the overall, not shown, and the portion 14 is doubled upon itself and has a buckle 16 on the end thereof which permits adjustment of the overall length of the portion 14. The portion 15 has a hook 20 20 on 15 thereon similar to hook 17 and serving the same purpose and also has a buckle 19 secured on the end thereof for adjustment of the overall length of portion 14.

It is thus seen that we have provided a garment 25 which is strong, durable, easy to wear, made of a minimum amount of material, providing a re-enforced back free from objectionable overlaps and unnecessary doubling of the material and other features which are apparent from the drawing.

In the drawing and specification there has been 30 set forth a preferred embodiment of the invention, and although specific terms are employed, they are used in a generic and descriptive sense 35 only, and not for purposes of limitation, the scope of the invention being set forth in the appended claim.

We claim:

A man's outer garment comprising right and 40 left leg portions, the rear portion of the leg portions extending upwardly to cover the central portion of the back of the wearer and having their outer edges cut away to provide arm space for the wearer, the extensions being joined together and 45 the extension for the right leg passing over the right shoulder of the wearer and the extension of the left leg passing over the left shoulder of the wearer, the proximate edges of the extensions being joined together by a seam to a point be- 50

tween the shoulders of the wearer, a quadrilateral re-enforcing flexible member secured to the said extensions, two opposed edges of said re-enforcing member being approximately parallel to the lines of force exerted by one of the extensions passing over one shoulder, and the other two edges of said quadrilateral member being approximately parallel to the lines of force exerted by the other extension passing over the other shoulder, where-
10 by shoulder stresses are absorbed by said re-en-

forcing member with a minimum amount of cov-
erage of the extensions by said re-enforcing mem-
ber, the front ends of said extensions having each
one end of an elastic section secured thereto, and
means on the other end of each elastic section for
releasably securing the elastic sections to the
front of the garment. 5
